ORLANDO R. ERWIN AND CURTIS B. FLORY, OF NEW YORK, N. Y., ASSIGNEES TO
FOAMITE FIREFOAM COMPANY, OF NEW YORK, N. Y., A CORPORATION OF
DELAWARE.

FIRE-EXTINGUISHING APPARATUS.

1,426,368.

Specification of Letters Patent. Patented Aug. 22, 1922.

Application filed June 3, 1920. Serial No. 386,200.

To all whom it may concern:

Be it known that we, ORLANDO R. ERWIN and CURTIS B. FLORY, citizens of the United States, and residents of New York city, in the county of Queens and State of New York, have invented certain new and useful Improvements in Fire-Extinguishing Apparatus, of which the following is a specification.

10 Our invention relates to fire extinguishing apparatus of the type employing a plurality of separate receptacles containing solutions which, when intermingled, produce a tenacious foam; and is particularly directed to improvements in the means for producing suitable pressure in the receptacles for delivering the solutions to the point of intermixture of application to the fire, this application being for the most part a continuation of our former application filed November 19, 1917, Ser. No. 202,728.

A primary characteristic inherent in the foam system of extinguishing fires is the fact that neither solution is employed directly for extinguishing fire, the solutions being intermingled at a suitable mixing station and losing their identity in the reaction, producing the foam which is applied to the fire. This characteristic makes it necessary to provide means for forcing each solution separately to the mixing point, an operation heretofore accomplished by injecting compressed air or steam into the solution containers. However, such an arrangement requires the employment of special apparatus for compressing the air or generating steam, and is particularly disadvantageous with the portable type of extinguisher.

A principal object of our invention is to provide simple and compact means for applying said pressure to the separate containers, eliminating the bulky and complicated apparatus heretofore employed. A further object is to produce a construction suitable for use with either stationary or portable apparatus, and which may be applied to the latter without materially increasing the bulk or weight thereof.

A specific object is to provide apparatus for producing delivery pressure in the containers operated entirely by the interaction of the solutions, eliminating the necessity for and employment of external sources of energy. This feature is highly advanta-

geous, not only with portable apparatus, which is thereby enabled to operate in any location without the use of portable engines or manual labor for producing pressure, but also in connection with stationary installations, which may be located at any desired point independent of sources of power for producing pressure, and without the concurrent installation and care of a power plant.

A further object is to provide a system of this type in which the delivery pressure can be readily varied and controlled. We have also disclosed a construction where the containers may normally be maintained at any desired pressure ranging from that of the atmosphere to and beyond the maximum delivery pressure. Furthermore, we have devised means whereby the pressure in the containers may be raised very rapidly to that necessary for the delivery of the solutions to the mixer and the propulsion of the foam onto the fire, thereby producing an apparatus which may be put into operation almost immediately without elaborate and lengthy preparation, a highly important feature in fire-fighting devices.

Other objects and advantages of my invention will be apparent from the following description, taken in connection with the accompanying drawings, in which:

Fig. 1 is a side view of a portable apparatus shown principally in central vertical section,

Fig. 2 is a side view of the apparatus shown in Fig. 1, with the mixing chamber located at a distance and in operative connection with a burning oil tank,

Fig. 3 is a detail sectional view of a preferred form of mixing chamber;

Fig. 4 is a diagrammatic perspective view partially in section of a stationary installation,

Fig. 5 is a side view of another type of portable apparatus, parts being broken away, and

Figs. 6, 7 and 8 are fragmentary end views of various modifications.

Our invention is applicable to systems of the foam type, in which a plurality of solutions are normally stored in independent containers. For convenience, I have illustrated a system of the ordinary two-solution kind, in which each solution is nor-

mally stored in a suitable separate container, such as tanks 10 and 11. Various solutions may be employed, such for instance as are disclosed in the patent to Erwin et al No. 1,225,944; and for convenience we will refer to the solution in tank 10 as the acid solution, and that in tank 11 as the alkaline solution, in conformity with the disclosure of said patent. Another formula 10 suitable for an engine of 500 gallons total capacity includes the following two solutions:

Solution A—375 gallons.

15 Water _____ 370 gallons.
Sodium bicarbonate _____ 278 pounds.
Pulverized soap bark _____ 30 pounds.

Solution B—125 gallons.

20 Water _____ 88 gallons.
Aluminum sulphate _____ 615 pounds.

As heretofore indicated, means is provided for conducting each solution from its container to a suitable mixing station. In 25 the construction shown in Fig. 1, we employ a suitable pipe line 12 having an inlet 13 adjacent the bottom of tank 10, and extending therefrom into a suitable mixing chamber 14 preferably located outside of the 30 solution containers. A similar pipe line 15 extends from an inlet 16 in tank 11 and adjacent the bottom thereof to the mixing chamber 14.

We employ means for conveying the foam 35 produced in chamber 14 to a suitable point for application to the fire, such as hose 17. Inlets 13 and 16 may be adapted to prevent solid matter from entering pipe lines 12 and 15, as by the employment of a suitable screen 40 arrangement which may be in the form of a perforated pipe as shown.

In general, we develop a suitable delivery 45 pressure in the solution containers by mixing a relatively small portion of the solution from tank 10 with a suitable amount of the solution from tank 11, and applying the pressure resulting from the expansion of the intermingled liquids to both tanks 10 and 11, the apparatus for accomplishing this 50 object being independent of that employed in conveying the separate solutions to the mixing point, such as chamber 14. One convenient and simple method of accomplishing this object consists in introducing a portion 55 of the solution from one container into contact with the solution in the other container, developing pressure at the latter point, and providing means for conveying such pressure to the first container.

60 This arrangement is disclosed in Fig. 1, in which we employ a suitable passage between tanks 10 and 11, such as piping 18, provided with a normally open inlet 19 in tank 10 and preferably adjacent the bottom thereof, and a suitable outlet 20 in tank

11, which may be at or near the top of said tank. We have found it convenient to shield inlet 19 against clogging, as by the employment of a perforated pipe section 21 connecting therewith, and to shield outlet 70 20 in a similar manner, as by a perforated pipe section 22. Either or both of the perforated pipe sections 21 and 22 may extend a substantial distance into the respective solutions to promote rapid and infallible 75 operation.

We provide means for introducing a portion of the solution from one container into the other when the development of pressure is desired. One construction suitable for 80 the purpose includes the arrangement of tanks 10 and 11 in such a position that the normal effect of gravity will cause the solution from one tank, such as tank 10, to flow through piping 18 into the other tank 85 11. When this arrangement is used, we provide means for normally closing the connection between the tanks, said means being of such a nature that it may be readily opened when pressure is desired. One convenient 90 form is operable manually, and may consist of an ordinary valve 23 in piping 18, provided with a handle 24 whereby the valve may readily be opened and closed at will.

With this construction, it will be apparent 95 that tanks 10 and 11 may normally be maintained at atmospheric pressure until the apparatus is needed for use, when the opening of valve 23 to a suitable extent by manipulation of handle 24 will permit a portion of 100 the acid solution to flow from tank 10 into tank 11, where it will interact with the alkaline solution therein, the resulting expansion raising the pressure in tank 11 proportionately to the amount of acid solution introduced thereon. As a result, the alkaline 105 solution in tank 11 is forced through piping 15 to the mixing chamber 14.

We provide means for transmitting to tank 10 the pressure developed in tank 11, 110 so that the acid solution may be forced simultaneously to the mixing point. This result is conveniently accomplished by connecting the upper part of tank 11 with the upper part of tank 10, as by piping 25, this 115 arrangement insuring an equal pressure in both tanks. Consequently, the generation of gas and an increase in pressure in tank 11 is accompanied by a simultaneous increase in tank 10, so that the two solutions are always under equal pressure. This arrangement insures the even flow of the acid solution from tank 10 into tank 11, and the simultaneous and equal delivery of the solutions to the mixing chamber 14, this feature 125 being important in a foam system, as the character of the foam is more or less dependent upon the intermixture of the component solutions in predetermined regulated proportions. Moreover, the pressure generated 130

can be varied at will by manipulation of valve 23, providing complete and ready control of the mixture and propulsion of foam.

In the specific embodiment shown in Fig. 5 1, we have found it convenient to mount the acid tank 10 directly above the alkali tank 11, as less acid than alkali is required in the production of foam according to the formula set forth in the above mentioned patent to 10 Erwin et al No. 1,225,944; and the tanks and solution conveying system are proportioned accordingly. The tanks may be mounted upon a suitable portable frame 26, and each tank is preferably provided with a filling opening 27, which normally is sealed by any suitable means, such as cap 28.

The piping systems connecting tanks 10 and 11 with the mixing station, when free from valves as in the form disclosed in Fig. 20 1, should of course rise at some point above the level of the respective solutions to prevent the flow thereof into the mixing chamber in the absence of delivery pressure in the tanks, the piping systems 12 and 15 in the 25 form disclosed extending from the top of each tank for this purpose.

The apparatus shown in Fig. 2 is in general of the same type as that disclosed in Fig. 1, being of the portable type; and is 30 shown as provided with the same means for generating delivery pressure in the tanks 10 and 11. However, the apparatus is adapted for use with mixing means located at some distance, this arrangement being desirable 35 where the tank 10 cannot be positioned immediately adjacent the fire, since the foam tends to lose its efficiency when transported for a long distance, unless the piping employed is of a size so large as to be impractical in connection with a portable apparatus.

We have illustrated an apparatus adapted for connection to a fixed installation which includes a mixer; and consequently the pipe 45 lines 12 and 15 do not connect at the apparatus, but communicate with means for connecting said lines to the fixed mixer. Various arrangements for this purpose can obviously be employed, the one illustrated including hose lines 29 connected to pipe systems 12 and 15, and adapted for ready coupling to fixed pipe connections 30 leading into the mixer 31. If desired, valves 32 may be inserted in pipe lines 12 and 15 to facilitate 50 control of solution flow without diminishing the pressure in the tanks 10 and 11, and similar valves 33 may be carried by the fixed installation connected to mixer 31. In the form shown, this installation is mounted 55 on a tank 34 of the type generally used for the storage of oil, and is provided with a riser 35 extending from mixer 31 to a point near the top of the tank 34, where outlet 36 directs the foam onto the surface of the tank 60 contents. This type of installation, how-

ever, is only one of various forms known to those skilled in the art, and is shown primarily for purposes of illustration.

One convenient construction for mixer 31 is shown in Fig. 3, in which the solution 70 pipes 30 communicate with a mixing chamber 37, which connects with the riser 35, pipes 30 being of different diameters if desired, so that the component solutions will be introduced into chamber 37 in proper 75 proportions.

In Fig. 4 we have shown one arrangement by which our invention may be applied to a fixed installation system. In this arrangement, we have shown a construction generally similar to that of Fig. 1, tanks 10 and 11 being mounted in fixed position. Certain variations in details have been disclosed, however, such as the extension of the pressure-equalizing pipe system 25 from tank 11 80 directly upward through the bottom of tank 10, terminating inside of and adjacent the top of the latter tank. One other variation includes the provision of a perforated inlet pipe 21 along the bottom of tank 10, and a 85 connection between pipe system 12 and tank 10 at the bottom of the latter, this arrangement being convenient where tank 11 is below the surface of the ground, tank 10 above the surface, and the piping systems are located on a plane between the tanks, as in the form illustrated. This arrangement, however, calls for the employment of valves 32 to prevent the intermingling of the solutions 90 under normal conditions.

Fig. 4 shows various connections which may be made between the fixed dual supply lines 12 and 15. At the left, we have shown the dual system as connected in the general manner shown in Fig. 2 to a similar mixer 105 31 communicating with a foam supply line 38, which extends to any suitable dispensing device, the line shown being connected with laterals 39 extending to the upper part of tanks 34 and operating in substantially the 110 manner described in connection with Fig. 2. Obviously, suitable valves 32 may be employed in controlling the flow of the solutions, and valves 40 inserted between the 115 foam line 38 and laterals 39.

Another arrangement, in which the two lines are delivered separately practically to the point of application to the fire, is shown at the right of Fig. 4, in which laterals 41 communicate with the distribution piping 120 systems 12 and 15 and terminate at a mixing station, which may be of the form shown in Fig. 2. Valves 42 preferably control the connections between the distribution lines and laterals 41.

Another dispensing arrangement suitable for use with this type of system is also shown in said system, and includes the valve controlled outlet 43 to which a hose 44 may readily be attached.

While we have disclosed various arrangements for distributing and dispensing the solutions and foam in a fixed installation of this type, it will be apparent that these forms are merely illustrative, as obviously a great many other connections, systems and arrangements may be employed in conjunction with the dual distributing systems 12 and 15; and our invention is not restricted to the 10 types disclosed or to mere variations in details thereof.

Another construction embodying our invention is illustrated in Fig. 5, and is shown as embodied in a portable apparatus with 15 tanks 10 and 11 mounted on a wheel-supported frame 45. In this form, the pressure equalizing pipe 25 extends from tank 11 upwardly through the bottom of tank 10, in substantially the same way as in Fig. 4, and 20 terminates above the general level of the top of tank 10 in a suitable housing or dome 46. We also may employ a safety valve 47 which may be mounted on dome 46. In this form, inlet 19 opens directly from the bottom of tank 10, and is protected from clogging by a screen 48. In this construction, we have found it convenient to extend the valve stem or handle 24 rearwardly along 25 tank 11 into a position where it may readily be manipulated by the operator, without interference with tanks 10 and 11. The outlet piping systems 12 and 15 are shown as provided with screen-covered bell mouth inlets 49, said systems communicating with 30 the two members of a dual hose line 50, which may be connected to any suitable mixing and dispensing means, such as nozzle 51, preferably similar in construction to that disclosed in the patent to Walker No. 40 1,299,272.

While we have disclosed several variations in a dual tank system, all of the forms above described are provided with tanks arranged on different planes, so that a solution may flow by gravity from one tank to the other. Such forms also show one of the tanks as serving not merely for the storage of solution, but also as a mixing reservoir to generate delivery pressure. Our invention, 45 however, is not limited to either of these arrangements; and in Figs. 6 to 8 we have shown a few of the numerous modifications in the arrangement of the tanks and the connections therebetween, and the mixing apparatus which may be employed within the scope of our invention.

In Fig. 6 we have disclosed tanks 10 and 11 arranged horizontally; but owing to the difference in size of the tanks in this specific 50 form, the lower portion of tank 10 is sufficiently above the bottom of tank 11 so that the piping system 18 connecting the bottoms of the tanks will be at such an angle that the acid solution will readily flow from tank 65 10 into tank 11 when valve 23 is opened.

The pressure equalizing pipe 25 connects the upper portions of the tanks in the manner heretofore described, and may have a valve 52 for controlling the transmission of pressure from tank 11 to tank 10, in case the solution in the latter tank should by any mischance be withdrawn more rapidly than that in tank 11. 70

In Fig. 7, the tanks are also arranged in substantially horizontal alinement, with a 75 pressure equalizing pipe 25 arranged similarly to that shown in Fig. 6. We have, however, disclosed a construction in which the pressure is generated not by transfer of a solution from one tank to the other, but 80 by the introduction into a tank of a suitable fluid from a separate container 53, the interaction of such fluid with the solution in the main tank producing an expansion of materials and a resultant pressure similar to 85 that above described. The solution in container 53, which is shown as communicating with tank 11, may be the same as that normally in tank 10; and in the form disclosed, the container 53 is mounted above tank 11 90 and connected therewith by a suitable piping 54 containing a valve 55 which, when open, will permit the fluid to flow from said container into tank 11.

An arrangement of a similar nature is 95 shown in Fig. 8, the pressure-producing fluid being carried by a container 56 of a portable type adapted to be connected to one of the tanks, for instance tank 11, as by flexible hose 57, the container 56 being provided 100 with a suitable pump or plunger construction actuated by handle 58 and adapted to force the fluid from the container 56 into tank 11 when and as required.

Various other modifications may readily 105 be substituted for those shown; and in particular, our invention is not restricted to the employment of one of the main fluid containers as a mixing chamber. Moreover, while the specific forms described employ 110 the actual solutions used in generating foam to produce the expansion which is employed in exerting delivery pressure, this arrangement may be varied, and other chemical agents may be utilized, either acting upon one of the main solutions or upon 115 each other, to generate gas which is applied equally to the main solution containers for developing delivery pressure therein. For instance, suitable carbonates may be introduced into the acid container to generate carbondioxide gas therein, without the production of foam, as is the case when gas is generated in the alkali solution of the type disclosed in the said patent to Erwin et al. 120 Furthermore, while the systems now in general use employ only two solutions, it will be apparent that if a three-solution system is found useful, our invention is equally applicable thereto, as the pressure may be 130

communicated with equal facility to any number of containers by suitable arrangement of the equalizing piping system 25.

We claim:

5. 1. Fire extinguishing apparatus, including a plurality of containers adapted for the separate storage of solutions which when mixed produce fire extinguishing foam, a separate delivery outlet for each container 10 adapted to be connected to a mixing station, and means for applying delivery pressure to the contents of each container including means for intermingling in one of the containers portions of the different solutions.
- 15 2. Fire extinguishing apparatus, including a plurality of containers adapted for the separate storage of solutions which when mixed produce fire extinguishing foam, a separate delivery outlet for each container 20 adapted to be connected to a mixing station, and means for applying delivery pressure to the contents of each container including means for transferring a portion of one solution from one container into contact with 25 the solution in another container.
3. Fire extinguishing apparatus, including a plurality of containers adapted for the separate storage of solutions which when mixed produce fire extinguishing foam, a 30 separate delivery outlet for each container adapted to be connected to a mixing station, and means for applying delivery pressure to the contents of each container including means for intermingling in one of 35 the containers portions of the different solutions and means for transmitting the resultant pressure to the other container or containers.
4. Fire extinguishing apparatus, including a plurality of containers adapted for the separate storage of solutions which when mixed produce fire extinguishing foam, a separate delivery outlet for each container adapted to be connected to a mixing station, and means for applying delivery pressure to the contents of each container including means for intermingling in one of the containers portions of the different solutions and a passageway connecting said container with the other container or containers 50 for transmitting the delivery pressure.
5. Fire extinguishing apparatus, including a pair of containers mounted in fixed position relative to each other and adapted 55 for the separate storage of solutions which when mixed produce fire extinguishing foam, a separate outlet for each container adapted to be connected to a mixing station, means for applying delivery pressure to the contents of both containers, comprising means for transferring a portion of a solution from one container into the other, including a passageway connecting the containers 60 having one end higher than the other and located below the level of one solution, the construction being such that the solution will normally flow by gravity through the passage from one container into the other, means for regulating the solution flow through said passage, and means for equalizing the delivery pressure in the container.
6. Fire extinguishing apparatus, including a pair of containers mounted in fixed position relative to each other and adapted 65 for the separate storage of solutions which when mixed produce fire extinguishing foam, a separate outlet for each container adapted to be connected to a mixing sta- 70
- ing a passageway connecting the containers above the respective solution levels.
7. Fire extinguishing apparatus, including a pair of containers mounted in fixed position relative to each other and adapted 75 for the separate storage of solutions which when mixed produce fire extinguishing foam, a separate outlet for each container adapted to be connected to a mixing station, means for applying delivery pressure to the 80 contents of both containers, comprising means for transferring a portion of a solution from one container into the other container including a passageway between containers and means for regulating the amount of solution which is transferred, and means for equalizing said delivery pressure in both containers, including a passageway connecting the containers above the respective solution levels. 85
8. Fire extinguishing apparatus, including a pair of containers mounted in fixed position relative to each other and adapted 90 for the separate storage of solutions which when mixed produce fire extinguishing foam, a separate outlet for each container adapted to be connected to a mixing station, means for applying delivery pressure to the contents of both containers comprising means for transferring a portion of a 95 solution from one container into the other container including a passageway between containers and means for manually regulating the amount of solution which is transferred, and means for equalizing said delivery pressure in both containers, including a passageway connecting the containers above the respective solution levels. 100
9. Fire extinguishing apparatus, including a pair of containers mounted in fixed position relative to each other and adapted 105 for the separate storage of solutions which when mixed produce fire extinguishing foam, a separate outlet for each container adapted to be connected to a mixing station, 110 means for applying delivery pressure to the contents of both containers, comprising means for transferring a portion of a solution from one container to the other, including a passageway connecting the containers 115 having one end higher than the other and located below the level of one solution, the construction being such that the solution will normally flow by gravity through the passage from one container into the other, means for regulating the solution flow through said passage, and means for equalizing the delivery pressure in the container. 120
- 125 10. Fire extinguishing apparatus, including a pair of containers mounted in fixed position relative to each other and adapted for the separate storage of solutions which when mixed produce fire extinguishing foam, a separate outlet for each container adapted to be connected to a mixing sta- 130

- tion, means for applying delivery pressure to the contents of both containers, comprising means for transferring a portion of a solution from one container to the other, 5 including a passageway connecting the containers having one end higher than the other and located below the level of one solution, the construction being such that the solution will normally flow by gravity 10 through the passage from one container into the other, manually operated means for regulating the solution flow through said passage, and means for equalizing the delivery pressure in the container.
- 15 10. Fire extinguishing apparatus, including two containers mounted with one end higher than the other and adapted for the separate storage of solutions which when mixed produce fire extinguishing foam, a 20 separate outlet for each container adapted to be connected to a mixing station, piping connecting the containers and adapted to convey the solution from one container into the other by gravity, a valve in said piping 25 for controlling the flow of solution therethrough, and a pressure equalizing duct connecting the containers.
11. In fire extinguishing apparatus of the described class, the combination of two substantially closed tanks, for normally storing two foam producing solutions separate from each other, said tanks being positioned adjacent one above the other, a chamber for mixing said solutions, a discharge outlet 35 duct connecting each of said solution tanks with said mixing chamber, a valved discharge outlet duct leading from said upper tank into said lower tank, a pressure equalizing duct inter-connecting the upper portions 40 of each of said tanks, and a discharge outlet duct for said mixing chamber.
12. In fire extinguishing apparatus of the described class, the combination of two substantially closed tanks, for normally storing two foam producing solutions separate from each other, said tanks being transportably mounted one above the other upon a wheeled truck, a discharge duct inter-connecting said solution tanks for the escape of said upper 45 solution into said lower solution, a pressure equalizing duct, inter-connecting the two storage tanks above the solution levels therein, a solution mixing chamber, ducts connecting said solution tanks with said mixing chamber, and valves for controlling the flow of said solutions in said ducts.
13. In fire extinguishing apparatus of the described class, the combination of two substantially closed tanks, for normally storing two foam producing solutions separate from each other, said tanks being positioned adjacent one above the other, a chamber for mixing said solutions, a discharge outlet duct connecting each of said solution tanks with 55 said mixing chamber, a valved discharge outlet duct for said mixing chamber, a
- outlet duct leading from said upper tank into said lower tank, a pressure equalizing duct inter-connecting said tanks, and a discharge outlet duct for said mixing chamber.
14. In fire extinguishing apparatus of the described class, the combination of two substantially closed tanks, one higher than the other, for normally storing two foam producing solutions, separate from each other, a duct inter-connecting said solution tanks, 75 for the passage of said upper solution into said lower solution, a pressure equalizing duct, inter-connecting the two storage tanks above the solution levels therein, a solution mixing chamber, ducts connecting said solution tanks with said mixing chamber, and valves for controlling the flow of said solutions in said ducts. 80
15. In a fire extinguishing system of the two-solution type adapted to employ solutions which, when intermingled, increase substantially in volume, a separate container for each solution, means for conducting each solution separately to a mixing station adjacent to the point of application to a fire 90 and means for transferring a portion of one solution from its container to the other container into contact with the other solution, to produce delivery pressure in said other container through interaction of the contacting 95 solutions.
16. In a fire extinguishing system of the two-solution type adapted to employ solutions which, when intermingled, increase substantially in volume, a separate container for each solution, means for conducting each solution separately to a mixing station adjacent to the point of application to a fire, means for transferring a portion of one solution from its container to the other container into contact with the other solution, to produce delivery pressure in said other container through interaction of the contacting solutions and means for applying 100 said delivery pressure to both solutions. 105
17. Fire extinguishing apparatus including a plurality of containers adapted for the separate storage of solutions which, when mixed, produce a fire extinguishing medium, a separate delivery outlet for each container adapted to be connected to a mixing station and means for applying delivery pressure to the contents of each container including means for bringing together in one of said containers a portion of one solution and 115 another substance to generate gas. 120
18. The method of extinguishing fires which consists in separately storing in solution tanks component solutions which, upon comixture, produce a fire extinguishing medium and in comixing in one of said tanks in time of fire one of the component solutions with another solution for the generation of a gas to exert operating pressure on the solutions in the tanks to drive them 125 130

through separate solution lines for subsequent comixture to produce a fire extinguishing medium.

19. The method of extinguishing fires
5 which consists in separately storing in solution tanks component solutions which, upon comixture, produce a fire extinguishing foam and in comixing in one of said tanks in time of fire one of the component solutions
10 with another solution for the generation of a foam to exert operating pressure on the

solutions in the tanks to drive them through separate solution lines for subsequent co-mixture to produce a fire extinguishing foam, said second comixture taking place at 15 a point remote from said first comixing.

Signed at New York city, in the county of New York and State of New York, this 1st day of June A. D. 1920.

ORLANDO R. ERWIN.
CURTIS B. FLORY.
